HENRY HARRISON SUPLEE, OF NEW YORK, N. Y.

AIRSHIP FORM.

1,412,297.

Specification of Letters Patent. Patented Apr. 11, 1922.

Application filed May 28, 1921. Serial No. 473,503.

To all whom it may concern:

Be it known that I, HENRY HARRISON SUPLEE, residing at New York city, in the county of New York and State of New 5 York, a citizen of the United States, have invented certain new and useful Improvements in Airship Forms; and I do hereby declare the following to be a full, clear, and exact description of the invention, such as 10 will enable others skilled in the art to which it pertains to make and use the same.

My invention relates to airships of the type known as lighter than air airships, and especially to that type known as rigid airships, in which the external form of the 15 carene or hull may be given a form in accordance with definite calculations.

Experience has demonstrated that when the carene or hull of an airship is given 20 such a form that it offers a minimum aerodynamic resistance the following advantages are attained: the power required to propel the ship through the air at a given speed becomes a minimum; or, the speed attained 25 for a given power becomes a maximum; the radius of action for a given fuel-supply becomes a maximum; and the stresses upon the airship and mooring-mast or tower, when the ship is moored in the open, be- 30 comes a minimum.

My invention consists in means for determining the form and proportions of the hull or carene of an airship which shall attain the before-mentioned objects, and in the 35 combination of the form and proportions of parts into a complete whole which shall have a minimum aerodynamic resistance under the conditions which may reasonably be encountered in practice.

40 The general form of an airship hull is that of a surface of rotation, being a spindle-shaped body, intended to be propelled through the air in the general direction of its axis. The lift, or supporting power of 45 such an airship is due to the buoyancy of the gas, lighter than air, with which it is filled, and hence the magnitude of this lift depends upon the volume of the body or hull. The problem, therefore, requires that 50 the determination of the best form of minimum resistance include a constant volume, otherwise the lift, or capacity, and consequently the size of the ship would become a variable. The requirements, therefore, are 55 that the volume, and the velocity of the ship remain constant, and that the ratio of max-

imum diameter to length, as well as the profile curve, which, revolved about its axis, gives the form, be varied according to a predetermined method.

In deriving means for determining the best form for an airship hull, I divide the total aerodynamic resistance into three parts; the head resistance; the surface friction; and the tail suction.

The head resistance opposed by the air to the entrance of the ship in its forward progress, corresponds practically to a uniformly distributed pressure, upon the projected maximum cross-sectional area of the 70 airship hull, and may be accurately determined for any given velocity in terms of said maximum cross-sectional area.

The surface friction, due to the viscosity of the air, as it drags upon the hull of the 75 ship during its forward motion, may be determined, for any given velocity, in terms of that portion of the surface of the hull of the ship upon which the air is pressed, and against which it rubs.

The tail suction, due to the inertia of the air, and consequent laps of time during 80 which the air closes in and fills the space from which the ship has moved in its forward progress, is constant for any given 85 speed, and is approximately measured by the difference between the head resistance and the friction of the hull for any given speed.

It follows that if the form of the hull be 90 so shaped that the tail suction be eliminated and the head resistance and skin friction made equal to each other and their difference consequently zero, the total resistance will become a minimum.

Theoretically the form which places the forces of a uniformly distributed load in equilibrium is that commonly known as the catenary; that is, the curve assumed by a chain of uniform weight per unit of length 100 when suspended from two points upon a horizontal line or by a flexible cord, thread or other flexible means, to which uniform weights are suspended at equal intervals.

This, then, is the form which, when revolved about the axis, gives a surface of rotation, forming the shape for the forward part of an airship hull which renders the head resistance a minimum.

If the forces which act to drag upon the 110 rearward portion of the hull were uniformly distributed, this portion would also best be

made in the form of a common catenary. The forces acting upon the rearward portion, are, however, as has already been stated, of two kinds; the skin friction, which 5 is practically uniformly distributed, and the suction, which is not uniformly distributed, but is concentrated at the tail. The most efficient form of the rearward portion of an airship hull, according to my invention, is 10 derived from a transformed catenary, obtained by suspending a chain or uniformly loaded cord or other flexible means from two points on a horizontal line, and adding thereto a tail loading, in the form of an 15 additional weight, spring, tension, or similar force, proportional to the tail suction on the same scale as the uniformly distributed forces.

This transformed catenary will then 20 respond to the profile of a shape in which the rearward drag of the skin friction, represented by the uniformly distributed forces, and the suction drag, represented by the additional force exerted upon the tail, 25 combine to produce the corresponding equilibrium curve. A surface of revolution, formed by revolving such a transformed catenary upon its axis, will have its tail drawn out to fill the space in which the 30 partial vacuum would otherwise be formed, and the drag of the suction will be practically eliminated.

The proportion of the whole airship hull which comes under the designation of the 35 forward portion, to that which is termed the rearward portion, varies somewhat with the velocity of the ship through the air. Experiments under various velocities show, however, that for a distance of about four-tenths of the entire length from the front 40 end of the hull, the surface of the ship is subjected almost entirely to direct air resistance, and that on this portion of the hull there is either no lateral surface pressure, or 45 even a slight negative lateral pressure. For this portion of the hull, therefore, there is little or no skin friction, because of the absence of normal surface pressure. For the remaining six-tenths of the length of the 50 hull there is a nearly uniform normal pressure, this acting to produce a practically uniform frictional drag over this rearward portion of the hull.

The ratio of maximum diameter to total 55 length of the hull varies somewhat according to the rate of speed at which the ship is intended to be operated, since the head resistance varies as the square of the velocity, and the frictional resistance varies as 60 a somewhat lower power, according to the character of the surface of the hull.

I have found that the most efficient form 65 of hull is that in which the head resistance and the frictional resistance are approximately equal to each other. If, therefore,

the maximum cross section be increased, the head resistance will also be increased, while if the length of the hull be increased, the frictional resistance will be increased. I have found that for very smooth surfaces 70 the length of hull which will make the frictional resistance approximately equal to the head resistance is that in which the total length is about nine and one-half times the maximum diameter; while for surfaces which are less smooth the length which gives 75 a frictional resistance equal to the head resistance may be only about seven and one-half times the maximum diameter; broadly, therefore I proportion the ratio of length to 80 diameter such that the head resistance and frictional resistance are approximately equal to each other to suit the particular conditions which arise in each case.

In general, the conditions which lead to 85 the determination of the most efficient form for an airship hull moving through the air with least resistance may be understood by imagining the hull to be composed of some gelatinous or soft material which could 90 adapt itself in form to the influence of the forces acting upon it. It will be evident that such a material would have a tendency to be drawn out to a tapering form in the rear by the drag of the viscous air pressed 95 against it, and pulled out at the tail by the suction at that point giving an additional drag, and that these influences are precisely imitated by the transformed catenary as described above. It is also evident that the 100 absence of any disturbing forces at that portion of the hull where the negative pressures are being reversed into positive pressures, would produce no effect on any such supposed soft or gelatinous body, so that the 105 location of the maximum cross section would be determined by the place of such reversal of pressure upon the hull. The forward portion, having upon it pressures parallel to the axis of the ship would maintain the form 110 of equilibrium corresponding to that of a chain or other flexible member under vertical loads, which is the common catenary, so that from such general conditions it is evident that the combination of common and 115 transformed catenaries, as in my invention, gives the outline of the form of minimum resistance.

The objects of my invention are attained by the means shown in the accompanying 120 drawing, in which similar reference characters refer to the same parts in the several figures.

Fig. 1, shows the general form of an airship hull according to my invention, the 125 ship being supposed to be proceeding through the air in the direction indicated by the arrow at 1. Fig. 2, shows a similar form of airship hull, exposed to the forces produced by the flow of air proceeding in the direc- 130

tion of the arrows at 1, or by the corresponding reactions when the airship is moving in the direction shown by the arrow in Fig. 1. Fig. 3, shows a transformed catenary with tail loading, for the determination of the form of the rearward portion of the hull. Fig. 4, shows the common catenary, as used for the determination of the form of the forward portion of the hull. Fig. 5, shows a catenary similar to that shown in Fig. 3, and for the same purpose, using a thread or cord, instead of a chain, with uniform weights suspended at equal intervals, and a spring tension for the tail loading, instead of the weight shown in Fig. 3. Fig. 6, shows a catenary for the determination of the form of the forward portion of the hull, using a thread or cord, with uniform weights suspended at equal intervals, instead of the chain shown in Fig. 4.

In Fig. 2, the small arrows show the general distribution of pressures upon an airship hull, as determined in the wind tunnel. The direct pressures upon the front portion of the hull act in a line parallel to the axis of the hull as indicated by the arrows 8-8, until about one-third to four-tenths of the length of the ship has been passed. At or about this portion of the hull, the pressures upon the hull become nearly zero, or are even slightly negative, as indicated by the arrows 9-9 turning outward, this region of zero pressure being about four-tenths of the length of the hull from the forward end 1. At the point 5, on the axis of the ship, is shown the maximum diameter of the hull, 3-4, the hull tapering aft nearly to a point, as shown at 2. The small arrows 10-10 shown in Fig. 2, from 2 to 3, and from 2 to 4, indicate that the air closing in upon the hull, exerts a nearly uniform pressure upon the surface, causing the frictional resistance upon this portion of the hull to be practically proportional to the area of the surface. At 2, the stream of air, closing in behind the tail at the rear end of the hull tends to form a partial vacuum, causing a suction of drag upon the tail. If the tail of the hull is made blunt, the space in which this vacuum is formed extends behind the airship in its progress, but if the tail of the airship is drawn out into the form assumed by this vacuum space, the greater part of this suction is prevented, and the resistance to the forward movement of the airship is thereby diminished.

In order to determine the correct profile curves to provide a shape of minimum resistance, I proceed as follows: Taking the maximum diameter of the hull, 3-4, laid off upon a horizontal line, as in Fig. 4, and drawing the axis 1-5 in a vertical position, as shown, I suspend a flexible chain 11, as

shown in Fig. 4, or a thread or cord 12, as in Fig. 6, permitting the chain or cord to assume the form of a catenary curve, lengthening or shortening the chain or cord until the lowest point of the curve is at 1, 70 this point 1, being the position of the nose of the hull. In Fig. 4, the chain 11, being of uniform weight per unit of length assumes the form of the common catenary; in Fig. 6, the thread or cord 12, has suspended 75 from its uniform weights 13 at equally spaced intervals, this arrangement giving a curve of similar form to that given by the chain 1 of Fig. 4. The catenary curve thus obtained is the equilibrium form for uniformly distributed equal forces, and gives 80 directly the profile of minimum resistance for the forward portion of the ship.

For the determination of the form of minimum resistance for the rearward portion 85 of the airship, I suspend a similar chain 14 from the extremities of a horizontal line 3-4 Fig. 3, the distance 3-4 being equal to the maximum diameter of the hull of the ship. The common catenary which such a 90 chain would assume would give the equilibrium curve for the uniformly distributed frictional forces. I then suspend to the bottom of this chain, at 2, Fig. 3, the weight 6, this weight being equal in magnitude to 95 the suction force acting upon the tail of the airship when in motion. This weight 6, transforms the catenary of Fig. 3, into the pointed shape, as shown, the pointed, tapering tail filling out the space which would 100 otherwise correspond to the suction vacuum behind the ship, preventing the eddying reactions which would otherwise be formed, and causing the air to pass off behind the ship in smooth stream lines. By using the 105 curve thus obtained in Fig. 3 for the rearward portion of the ship, and the curve obtained in Fig. 4, for the forward portion of the ship, the form shown in Fig. 1, is obtained, giving the minimum resistance to 110 the passage through the air. Fig. 5, shows the use of a thread or cord 15, with uniform weights 16, suspended at equal intervals, instead of a chain for the determination of the catenary curve, and also shows the use of a 115 spring 7, instead of a weight 6, for the additional loading at the tail, corresponding to the tail suction.

The magnitude of the load to be added to the bottom of the catenary, as shown in Fig. 3 or Fig. 5, to correspond to the tail suction may be obtained by measurement in the wind tunnel, or it may be obtained with approximate accuracy by making it equal in weight to that of a length of the chain equal 120 to the difference between the lengths of chain for the determination of the forward portion and that for the rearward portion of the airship hull.

Experience has shown that the total re- 130

sistance to the progress of the ship through the air is a minimum when the resistance of the two portions of the ship are equal to each other. This equality of resistance occurs 5 when the ratio of length 1—2, is from seven and one-half to nine and one-half times the maximum diameter 3—4, the greater ratio existing when the surface of the airship is very smooth, and the ratio diminishing when 10 the surface of the airship is rougher, or when the frictional resistance is materially increased by reason of irregularities in form or protuberances upon the ship.

I do not wish to be understood as limiting 15 myself to the specific details of construction and arrangement as herein described and illustrated, as it is manifest that variations and modifications may be made in the features of construction and arrangement in 20 the adaptations of the method to various conditions of use without departing from the spirit and scope of my invention and improvements. I therefore reserve the right to all such variations and modifications 25 as properly fall within the scope of my invention, and the terms of the following claims.

What I claim is:

1. A form for airships of which the forward portion consists of a surface of revolution 30 derived from revolving a catenarian curve upon its major axis.

2. An airship form of which the rearward portion consists of a surface of revolution 35 derived from revolving a transformed catenarian curve upon its major axis, said transformed curve being derived by applying tension to the lower end of said catenarian curve proportional to the suction force acting upon the tail of the airship when in motion.

3. An airship form comprising a portion consisting of a transformed catenarian surface of revolution derived from rotating a 45 transformed catenarian curve upon its major axis and means for causing the trans-

formation of said surface by applying loadings proportional to the forces acting upon the airship when it is in motion.

4. A form for airships having a rearward portion comprising a surface of revolution derived from rotating a transformed catenarian curve upon its major axis and means for transforming said portion by applying to the sides a vertical tension proportional to the surface frictional forces acting during motion, and simultaneously applying to the lowermost point of the curve a vertical tension proportional to the suction force acting upon the tail when the airship is in motion. 60

5. In an air ship form the ends of which have catenarian surfaces of revolution about major axes, means for producing the same comprising a chain and tension applied to the lower portion thereof for the purpose of 65 causing the shape of said chain to be transformed to a degree proportional to the suction force acting upon the tail of the airship when in motion.

6. In an airship form the ends of which have catenarian surfaces of revolution about major axes, means for producing the same comprising a chain or other flexible means, loadings applied at intervals to said chain the weights of which are proportional to the 75 forces acting upon the profile curve when the ship is in motion.

7. The method of determining a profile curve for an airship consisting in suspending a chain or other flexible means from the extremities of a horizontal line equal in length to the maximum diameter of said airship, applying to said chain or flexible means tensions proportional to the aerodynamical forces acting upon said airship 85 when in motion through the air, or when stationary in a wind tunnel or chamber and rotating said chain or means upon its major axis.

In testimony whereof I have affixed my 90 signature.

HENRY HARRISON SUPLEE.
